UNITED STATES PATENT OFFICE.

GEORGE W. CAMPBELL, OF COLUMBUS, OHIO.

MORTISING-MACHINE.

Specification of Letters Patent.

Patented Dec. 31, 1918.

1,289,114.

Application filed March 2, 1916. Serial No. 81,692.

To all whom it may concern:

Be it known that I, GEORGE W. CAMPBELL, a citizen of the United States, residing at 5 Columbus, in the county of Franklin and State of Ohio, have invented certain new and useful Improvements in Mortising-Machines, of which the following is a specification.

This invention relates to improvements in 10 mortising machines, the improvements relating more particularly to the machine described in my application Ser. No. 780,625, filed July 23rd, 1913.

One of the objects of the invention is to 15 improve the tool oscillating mechanism, first, by providing more effective devices for reversing the direction of movement of the mechanism; second, to provide for more uniformly regulating the length of the mortise; third, for providing an improved 20 swiveled connection between the tool carrier and the oscillating mechanism for the same; and fourth, to generally simplify and make more effective the operation of the 25 oscillating mechanism as a whole.

A further object of the invention is to 30 simplify and make more effective the means for causing the tool to travel in a straight line throughout the length of the mortise and in this connection to also provide for 35 eliminating lost motion in the tool and its carrier, thereby preventing the tool from being drawn into the work by hooking.

A further object of the invention is to 40 simplify and make more effective the general construction of mortising machines of the character referred to.

In the accompanying drawings:—

Figure 1 is a side elevation of a machine 45 embodying my improvements.

Fig. 2 is an enlarged view, partly in section, of the reversing mechanism shown in Fig. 1.

Fig. 3 is a section on the line 3—3 of 50 Fig. 1.

Fig. 4 is a longitudinal section of the tool holder and some of its associated parts.

Fig. 5 is a section of the connection between the tool holder and the screw.

Figs. 6, 7 and 8 are details of parts of the 55 reversing mechanism.

In the drawings, 1 and 2 are guide rods connected together at one end of the ma-

chine by the handle portion 3 and at the other end of the machine by a slotted cross-bar 4, the upper and lower ends of which are provided with suitable clamps 5 for attaching the machine to the door or other work to be mortised as more fully shown in my pending application referred to. The carriage for the operating parts is slidably mounted upon the guide rods 1 and 2 and consists of side pieces 6 and 7, a rear connecting piece 8, forward connecting pieces 9 and 10 and a central cross piece 11; the carriage being provided with laterally extending bosses 12 which are sleeved upon the guide rods 1 and 2.

Journaled in the cross piece 11, the central portion of which is offset or depressed, and also in a small bracket 13 secured thereto is a shaft 14 to one end of which is connected a main operating wheel 15; a collar 16 serving to hold the shaft and wheel 15 against longitudinal displacement. Pivoted 75 upon the shaft is a tool holder 17, the holder being provided with an elongated opening 18 through which the shaft extends, the elongation of the opening being for a purpose to be explained hereinafter. The forward end of the holder is bored out to receive the shank 19 of the tool, an anti-friction ball 19^a being preferably inserted between the inner ends of the shank and socket. The holder is also provided with 80 an open-sided enlargement or housing 17^a within which is located a pinion 20 secured to the tool shank. The pinion 20 is in mesh with the teeth 21 on the side of the operating wheel 15 so that when the wheel is operated the tool will be revolved.

Tool oscillating devices.

Revolutionally mounted in bearings 22 which extend laterally from the carrier frame is 95 a screw 23 upon which is threaded a head 24. The head 24 is swivelly connected with a block 25, which has a pin or stud 26 projecting into a recess in the head for this purpose. The block 25 is slidably mounted 100 in ways 27 integrally formed with the tool holder 17, for the purpose hereinafter explained. Loosely mounted upon an unthreaded portion of the screw 23 are bevelled gears 28 and 29 and splined to the unthreaded portion of the screw between these 105

gears is a clutch member 30 arranged to be shifted along the screw so as to be thrown into operative relation with either one of the gears. The clutch member is in the form 5 of a grooved collar having on each side thereof a projecting tooth 31 and 32 each one of which is arranged to be thrown into the path of teeth 33 and 34 on the respective gears. A beveled pinion 35, is in mesh 10 with each of the gears 28 and 29 and has its shaft journaled in the frame of the carrier, the opposite end of the shaft being provided with a pinion 36 (shown in dotted lines in Fig. 1) in mesh with the internal gear teeth 15 37 on the main operating wheel so that as said wheel is operated the gears 28 and 29 will be rotated in opposite directions. Pivotedally connected to a supporting block 38 projecting laterally from the carrier frame, 20 by a pivot screw 40 is a shifting lever 39. One arm 41 of this lever is forked and straddles the grooved clutch collar 30. The other arm is bifurcated, the members 42 and 43 extending at right angles to the forked portion 41 and being provided with right angled ends 44 and 45 in which is slidably mounted a rod 46 having fixed thereon a block or collar 47. Between this collar 47 and each of the right-angled ends 44 and 30 45 are coil springs 48 and 49. Pivotedally connected to the collar 47 by a pivot screw 50 is a shifting arm 51 which is pivoted upon the pivot screw 40, as a result of which when the shifting arm 51 is swung about its 35 pivot in the manner now to be described, the lever 39 will also be tilted so as to shift the clutch 30 by reason of the tension placed upon either one of the springs 48 or 49 because of the movement of the block 47 and 40 the rod 46; means being provided, however, for preventing the shifting of the lever 39 until a spring has been placed fully under tension. This means consists of two pivoted latches 52 and 53 each of which is provided 45 with a shoulder 54 and a beveled portion 55. When the lever 39 is shifted to one position the shoulder on one of the latches will engage a projection 56 and retain the lever in its shifted position. The lever will be held 50 in this position until near the extreme limit of the movement of the shifting device to be described later, but will be finally released by a beveled projection 51^b on the arm 51 coming in contact with the inclined portion of the latch which forces the latch 55 out of engagement with the projection on the lever after one of the springs has been placed under tension by the movement of the arm 51. The spring then quickly shifts 60 the lever so as to throw the clutch 30 from one gear to the other, the latch being at the same time returned to normal latching position by a spring 63. The shifting of the arm 51 to accomplish this begins to take 65 place near the end of each oscillatory move-

ment of the tool holder. Slidably mounted on the carrier frame is a bar 57 which has rotatably mounted therein a screw 58 one half of which is provided with left-hand threads and the other with right-hand 70 threads. Threaded on each half of this screw are sleeves 59 and 60 each of which has a pin 61 which projects through a slot extending the length of the bar 57. The screw 58 has a knurled finger piece 62 by 75 which it may be turned so as to simultaneously and uniformly adjust the pins 61 to or from the center of the machine; the pins on the sleeves, which, as before stated, extend through a slot on the bar, preventing the 80 sleeves from turning with the screw. The bar is provided with a laterally extending fork 64 which straddles the end of the shifting arm 51 so that when the tool holder strikes one of the pins and moves the bar 57 85 90 95 the shifting arm 51 will be swung about the pivot 40 and carry with it the rod 46 and its block placing one of the springs 48 or 49 under tension, and then by reason of the beveled projection on said arm, finally releasing the latch which is holding the lever 39 so as to permit the shifting of this lever by the spring which has been placed under tension. The shifting arm is also provided with projecting fingers 65, which, in the event that for any reason the spring fails to throw the lever 39, will contact the projection 56 thereon and positively move the same for a short distance, the spring then completing the movement of the lever; these 100 105 fingers acting in the nature of make-sure devices. The opening 51^a in the arm 51 through which the pivot pin 50 extends is elongated as shown in Fig. 7 so as to allow for the necessary movement of the parts. 105

Tool feeding devices.

As is usual in machines of this character, means are provided for feeding the tool into the mortise at the end of each oscillatory 110 movement of the tool carrier. In the present machine this is accomplished as follows:—Mounted in a bracket 66 secured to the guide rail 1 is a screw 67, the lower end of which is journaled in a bearing 68 on 115 the carrier frame and is provided with a ratchet wheel 69. Secured to the shiftable bar 57 on each side of this ratchet wheel are spring pawls 70 which alternately engage the ratchet wheel at the end of each 120 oscillatory movement of the tool carrier and thereby turn the screw through a portion of a revolution. A plunger 71 located in the bracket 66 is normally held in engagement with the threads of the screw by 125 a spring 72 so that each time the screw is revolved the carriage and consequently the tool will be moved toward the work. When it is desired to return the carriage to a proper position for a fresh mortise the 130

plunger 71 is pulled out of engagement with the screw so that the carriage may be readily slid along the guides 1 and 2.

5 *Devices for causing the tool to travel in a straight line.*

The central portion of the cross bar 8 is formed with a curved off-set 8^a and the rear end of the tool holder is recessed to receive 10 this off-set portion. Anti-friction balls 73 and 74 are carried by the holder on each side of the cross bar, the ball 73 being located in a recess in the holder on one side of the bar and the ball 74 in a chambered 15 portion 75 on the opposite side of the bar, a spring 76 being interposed between the ball 37 and the end of the recess and the chambered portion being closed by a plug 71^a. As before explained, the holder at the 20 point where it is pivoted upon the shaft 14 is provided with an elongated opening 18, and also, as before explained, the block 25 which connects the tool holder with the screw 23 through the medium of the head screw 24, is slidably mounted in ways 27. This 25 construction allows the tool holder and tool a longitudinal movement relative the other parts, this movement being determined by the curvature of the central portion 8^a of the bar 8 as the tool holder rides thereon during the oscillatory movement, the curvature of this bar being such as to cause the cutting end of the tool to travel in a straight line throughout the entire 35 length of the mortise.

In the former construction of the curved off-set portion 8^a it was necessary to vary the thickness of the same to prevent binding, the thickest portion being at the center 40 and the bar gradually tapering therefrom. In a construction such as shown in my former application referred to, this variation and thickness of the bar caused more or less lost motion since the distance between the 45 anti-friction balls cannot be varied. This lost motion caused the tool to be drawn into the work by hooking in a knot or cross mortise. By the construction above explained, however, in which a spring is employed, the inner curved surface of the 50 crossbar is always kept in contact with the forward ball 73, the spring being sufficient to overcome the pressure of the working action of the tool, which, of course, is rearward.

By the manner of pivoting the tool holder upon the shaft 14, in which it will be seen the shaft extends entirely through the tool holder and bracket 13 and beyond the same, 55 provision is made for the attachment of a crank whereby the operator may use both hands in operating the machine.

By employing the oppositely threaded screw for the pins 61, these pins may be 60 simultaneously and also uniformly adjusted

relative to the center of oscillation of the tool, which eliminates accurate measurement in adjusting for different sized mortises as well as enabling the adjustment to be more quickly made. This arrangement 70 also prevents the pins from working loose as sometimes happens when thumb nuts are employed for holding them in their adjusted positions.

By the arrangement described in connection with the clutch shifting mechanism, an effective shift is accomplished at the proper point at the end of the oscillatory movement of the tool. By reason of employing 75 but a single tooth on each of the driving pinions in connection with a single tooth on each side of the clutch collar, another desirable result is obtained in that the tool will generally be permitted a certain number of revolutions before the pinion picks 80 up the clutch for the purpose of reversing the motion of the screw-feed for the tool holder, thus enabling the tool to clear itself of accumulated cuttings.

Having thus described my invention, I 90 claim:

1. In a mortising machine, an oscillatory tool, a screw having an operative connection with said tool, means for rotating said screw in opposite directions comprising a 95 shiftable clutch, a pivoted shifting lever for said clutch, a pair of springs carried by said lever, a pivoted arm between said springs, a latch for said lever in each of its positions, a slideable bar operatively connected with 100 said arm, and adjustable projections on said bar with which said tool contacts at the end of each oscillatory movement whereby one or the other of said springs is placed under tension and the lever released by tripping 105 one or the other of the latches together with means for simultaneously adjusting said projections.

2. In a mortising machine, an oscillatory tool, a screw having an operative connection with said tool, means for rotating said screw in opposite directions comprising a shiftable clutch, a pivoted shifting lever for said clutch, said lever having a bifurcated 110 end, a guide rod supported by said bifurcated end, a pair of springs on said rod, a slideable block on said rod between said springs, a pivoted shifting lever having a pivotal connection with said block, a latch 115 for said lever in each of its extreme positions, a slideable bar operatively connected with said arm, and adjustable projections on said bar with which said tool contacts at the end of each oscillatory movement thereof whereby one or the other of said springs is 120 placed under tension and the lever released by tripping one or the other of said latches together with means for simultaneously adjusting said projections.

3. In a mortising machine, an oscillatory 125

- tool, a screw having an operative connection with said tool, means for rotating said screw in opposite directions comprising reversing mechanism, an operating device for said reversing mechanism comprising two projections arranged in the path of said tool, and means for simultaneously and uniformly adjusting said projections.
4. In a mortising machine, an oscillatory tool, a screw having an operative connection with said tool, means for rotating said screw in opposite directions comprising reversing mechanism, operating devices for said reversing mechanism comprising two projections arranged in the path of said tool, a shiftable screw having right and left hand threaded portions, a projection being threaded upon each one of said portions together with means for holding said projections from turning whereby said projections may be simultaneously and uniformly adjusted.
5. In a mortising machine, an oscillatory tool, a screw having an operative connection with said tool, means for rotating said screw in opposite directions comprising reversing mechanism, an operating device for said reversing mechanism comprising a shiftable bar, a screw rotatably mounted in said bar having right and left hand threaded portions, and two projections threaded on the respective threaded portions and projecting through a slot in said bar whereby said projections may be simultaneously and uniformly adjusted.
6. In a mortising machine, a support, an oscillatory tool pivotally connected to said support, the connection being such as to permit a movement of said tool relative thereto, mechanism for oscillating said tool, the connection between the tool and mechanism being such as to permit a movement of said tool relative thereto, a curved track extending through a recess associated with said tool to cause the tool to be projected and withdrawn relative to said support, and a spring inserted between said track and tool for the purpose of placing a yielding pressure thereon.
7. In a mortising machine, a support, an oscillatory tool holder pivotally connected to said support together with a tool carried thereby, said holder having a slotted opening at the pivotal connection of said support, mechanism for oscillating said holder, a connection between said mechanism and holder comprising a swiveled block slidably connected with said holder, and means whereby said holder and tool is projected and withdrawn relative to said support during the oscillatory movement thereof.
8. In a mortising machine, a support, an oscillatory tool holder pivotally connected with said support together with a tool carried thereby, mechanism for oscillating said carrier, the connection of said holder with said support and also with said mechanism being such as to permit a longitudinal movement of said holder relative to said support and mechanism, a curved track on said support extending through a recess in said holder, anti-friction balls arranged on opposite sides of said track and between the same and said holder, and a spring arranged between one of said balls and said holder.
- In testimony whereof I have hereunto set my hand this 18th day of February, 1916.
- GEORGE W. CAMPBELL.
